UNITED STATES PATENT OFFICE

HAROLD S. LOOMIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed June 3, 1926. Serial No. 113,382.

My invention relates to railway traffic controlling apparatus, and particularly to apparatus of the type comprising devices located in the trackway adapted to co-operate with train carried means to control the progress of the train.

More particularly my invention relates to means for checking the circuits of the trackway devices in such apparatus.

10 I will describe one form of trackway apparatus embodying my invention, and then point out the novel features in claims.

15 The accompanying drawing is a diagrammatic view showing one form of trackway apparatus embodying my invention.

Referring to the drawing, reference characters 1 and 1^a designate the track rails of a stretch of railway track which is divided into sections A—B, B—C, etc., by means of insulated joints 2. Each section is supplied with track circuit current from a suitable source such as a battery 3. Connected to the track rails of each section near the entrance end is a track relay designated by 20 the reference character R with an exponent corresponding to the location. Associated with each track relay R is a line relay designated by the reference character H with a suitable exponent, and controlled jointly by 25 front contacts of the associated track relay and the track relay of the section next in advance.

30 Each track section is also provided with a trackway signal designated by the reference character S with an appropriate exponent. The signals S are here shown as three-position semaphore signals, each of which is placed adjacent the entrance end of the associated section, and is capable of indicating "stop", "caution" and "proceed", although this particular form and location of the signals is not essential.

35 Adjacent the entrance end of each track section, I also provide a trackway inductor designated by the reference character K with a suitable exponent. Each inductor K comprises a core 4 carrying a winding 5, and is adapted to co-operate with train carried apparatus in such manner that an automatic application of the brakes occurs or a stop in-

5 dication is given on a train passing an inductor with its winding 5 open circuited, but no effect is produced on a passing train when the circuit of the winding is closed. The train carried apparatus is not illustrated because it forms no part of my invention. Preferably the trackway inductor for each section is located in the rear of the entrance end of the associated section by a distance equal to the distance required to bring a train 60 having longest braking distance from the highest permissive speed to a full stop.

55 The winding 5 of each inductor K forms a part of a completely isolated circuit including a checking relay J, a battery G and a front contact 8 of the associated relay H. By "isolated" I mean that no part of the inductor circuit is at any time, electrically connected with any other circuit. Whenever a line relay such as H^B is energized the winding 5 of the associated inductor K^B is close circuited through a circuit from battery G^B, front contact 8 of relay H^B, wire 9, winding 5, wire 6, relay J^B and wire 7 back to battery G^B. Inductor K^B will then produce no effect on 70 a passing train, but if relay H^B is de-energized, the brakes will be applied or a stop indication will be given on a train passing the inductor K^B.

75 It will now be clear that opening of contact 8 will introduce practically an infinite resistance into the circuit of winding 5, so that a brake application or a stop indication on a passing train will be assured, and also that a fault such as a broken wire in the circuit of the inductor winding 5 will render it impossible to close circuit this winding, hence the brakes on a passing train will be applied or a stop indication will be given to warn the engineman of an abnormal condition in the 80 trackway apparatus.

85 Associated with each signal is a circuit controller designated by the reference character L, which circuit controller is closed when the signal indicates proceed or caution, but not when the signal indicates stop. This circuit controller governs the line relay H for the section next in the rear. The circuit for relay H^A, for example, is from battery P^B, through wire 10, circuit controller L^B for 90 95 100

signal S^B , contact 11 of relay R^B , wire 12, contact 13 of relay R^A , line relay H^A , and wires 14 and 27 back to battery P^B . It is thus to be seen that line relay H^A cannot be energized unless the associated track relay R^A and the track relay R^B of the section next in advance are energized, and signal S^B indicates either proceed or caution.

Each signal is provided with a caution circuit and a proceed circuit. The caution circuit for signal S^B , for example, is from battery P^B , through wires 10 and 15, contact 16 of relay R^B , wire 28, back contact 17-18 of relay H^B , back contact 19-20 of checking relay J^B , wire 21, signal S^B , and wire 14 back to battery P^B . This caution circuit is closed when track relay R^B is energized and relays J^B and H^B are both de-energized. Each signal S also has an auxiliary caution circuit which is closed only when the signal indicates "proceed". This circuit is from battery P^B , through wires 10 and 15, contact 16 of relay R^B , wire 28, front contact 17-22 of relay H^B , front contact 20-23 of relay J^B , wire 21, signal S^B and wire 14 back to battery P^B . The proceed circuit for signal S^B is from battery P^B , through wires 10 and 15, contact 16 of relay R^B , wire 28, front contact 17-22 of relay H^B , front contact 20-23 of relay J^B , wire 24, front contact 25 of relay H^B , wire 26, signal S^B , and wire 14 back to battery P^B . This proceed circuit is closed only when relays J^B and H^B are both energized.

When relay H^A is energized, if inductor K^A should become displaced so as to break a wire, for example, wire 6, relay J^A would be de-energized and contact 20-23 of relay J^A would open both the proceed and caution circuits for signal S which would therefore give a stop indication. It will also be obvious that the use of a completely isolated inductor circuit prevents the inductor winding from being close circuited by a ground in the system.

As shown in the drawing, the section to the right of point C is occupied by a train indicated diagrammatically at V. Relay R^C is, therefore, de-energized and contact 16 has opened both the caution and proceed circuits for signal S^C which, therefore, indicates stop. Contact 13 is open so that relay H^C is de-energized, and winding 5 of inductor K^C is open circuited by opening of contact 8. Contact 11 of relay R^C is open, so that line relay H^B is de-energized, inductor K^B is open circuited at contact 8 of relay H^B , and signal S^B indicates caution. Relays R^A , J^A and H^A all being energized, signal S^A indicates proceed and the circuit for inductor K^A is closed.

I will now assume that a train equipped with automatic controlling apparatus enters the stretch of track shown in the drawing, proceeding from left to right.

As the train passes the inductor K^A , the train carried apparatus will not be affected

because the winding 5 is close circuited. When the train passes inductor K^B , however an automatic application of the brakes will be made since the winding 5 is open circuited by open contact 8 of relay H^B . If the train continues past the inductor K^C it will receive a second brake application because the winding 5 of inductor K^C is also open circuited.

If an open circuit or a break should occur in winding 5 of inductor K^A or in any part 75 of its circuit, a train approaching point A would incur a brake application as it passed the inductor K^A . Such a break, however, would cause de-energization of relay J^A thus opening front contact 20-23 of this relay and causing the signal S^B to indicate "stop," which in turn would cause the signal next in the rear to indicate "caution" because circuit controller L^A would be open. It will thus be seen that a signal can never indicate "proceed" with the associated trackway inductor open circuited.

Although I have shown and described but one form of trackway apparatus embodying my invention, it is understood that various changes and modifications may be made therein within the scope of the appended claims without departing from the spirit and scope of my invention.

Having thus described my invention what I claim is:

1. In a railway traffic controlling apparatus, the combination with a section of track and a trackway signal, of a track relay connected to the section, a line relay having a back contact and a plurality of front contacts and jointly controlled by the track relay of the adjacent section and the section next in advance, a trackway inductor, a winding on the inductor, a circuit for said inductor winding including a checking relay and a front contact of said line relay, said checking relay having a front and a back contact, a caution circuit for the signal including a back contact of the checking relay and a back contact of the line relay, and a proceed circuit for the signal including the front contact of the checking relay and two front contacts of the line relay.

2. In combination, a plurality of sections of railway track, a track relay associated with each section, a signal capable of giving a more or less restrictive indication depending upon traffic conditions in advance, a trackway inductor for the automatic control 120 of trains, a circuit for said inductor including, a checking relay, a line relay jointly controlled by the track relay of one section and by the track relay of the section in advance, and means operative only when the checking and line relays are energized to cause the signal to give one indication, and when both are de-energized to give another indication.

3. In combination, a section of railway track, a trackway signal capable of giving a

more or less restrictive indication depending upon traffic conditions in advance, a trackway inductor for the automatic control of trains, a circuit for said inductor including a checking relay, a line relay, a source of current for energizing the line relay, and means operative only when both of said relays are energized to cause the signal to give one indication and when both are de-energized to give another indication.

4. In combination, a section of railway track, a trackway signal capable of giving a more or less restrictive indication depending upon traffic conditions in advance, a trackway inductor, a winding on the inductor, a checking relay and a source of current in series with the winding, a line relay and means for energizing it, and means operative only when both of said relays are energized to cause the signal to give one indication, and when both are de-energized to give another indication.

In testimony whereof I affix my signature.
HAROLD S. LOOMIS.
